CLAIM

The ornamental design for a combined multiple mascara dispenser and applicator, as shown and described.

DESCRIPTION

FIG. 1 is a perspective view of a combined multiple mascara dispenser and applicator showing my new design with the applicator partially extended.

FIG. 2 is a side elevational view thereof;

FIG. 3 is a top plan view thereof;

FIG. 4 is a bottom plan view thereof; and

FIG. 5 is a cross-sectional view taken along the line 5—5 in FIG. 1.
